UNITED STATES PATENT OFFICE.

JOSEPH H. GLAUBER, OF CLEVELAND, OHIO.

DESIGN FOR A HANDLE FOR FAUCETS AND OTHER ARTICLES.

45,227.

Specification for Design.

Patented Feb. 10, 1914.

Application filed November 1, 1912. Serial No. 729,151. Term of patent 14 years.

To all whom it may concern:

Be it known that I, JOSEPH H. GLAUBER, a citizen of the United States, residing at Cleveland, county of Cuyahoga, and State of Ohio, have invented a new, original, and ornamental Design for a Handle for Faucets and other Articles, of which the following is a specification, reference being had to the accompanying drawing, forming part thereof, in which—vation, and Fig. 3 an end elevation, showing my new design.

I claim:

The ornamental design for a handle for faucets and other articles, as shown.

JOSEPH H. GLAUBER.
